CONVERTIBLE SADDLE BRIEF CASE

Sidney Norinsky, 110 W. 96th St.,
New York, N.Y. 10025

Filed Dec. 9, 1974, Ser. No. 530,700

Term of patent 14 years

Int. Cl. D3—01

U.S. Cl. D87—5 B

FIG. 2

FIG. 3

FIG. 1 is a perspective view of a convertible saddle brief case showing my new design in a collapsed condition, a corner of one flap being folded upwardly to expose the overlapping end gussets;

FIG. 2 is an enlarged scale top plan view shown in an expanded condition with the intermediary web exposed;

FIG. 3 is a rear elevational view thereof;

FIG. 4 is an end elevational view; and

FIG. 5 is a bottom plan view.

I claim:

The ornamental design for a convertible saddle brief case, as shown and described.
